(57) CLAIM

The ornamental design for a card deck box as shown and described.

DESCRIPTION

FIG. 1 is a perspective view of a card deck box showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a perspective view of the card deck box in an alternate configuration;

FIG. 10 is a perspective view of the card deck box in an alternate configuration

FIG. 11 is a partial enlarged view of portion 11 in FIG. 1; and,

FIG. 12 is a partial enlarged view of portion 12 in FIG. 2. The broken lines depict portions of the card deck box and form no part of the claimed design.
